UNITED STATES PATENT OFFICE.

CHARLES C. R. HAMMAR, OF SAN FRANCISCO, CALIFORNIA.

KEY-PULLING DEVICE.

1,273,484.

Specification of Letters Patent. Patented July 23, 1918.

Application filed July 30, 1917. Serial No. 183,645.

To all whom it may concern:

Be it known that I, CHARLES C. R. HAMMAR, a citizen of the United States, residing in the city and county of San Francisco, 5 State of California, have invented a new and useful Key-Pulling Device, of which the following is a specification in such full and clear terms as will enable those skilled in the art to construct and use the same.

10 This invention relates to a key pulling device and its object is to remove headed keys from their secured position upon a rotary shafting having the mounted member thereon.

15 One of the objects of the invention is to produce a key puller that is simple but effective, the low cost of which will allow for its extensive use, the device being standardized in variable sizes.

20 With these objects in view, the invention comprises various features of construction, as hereinafter set forth in the following description in which the same numeral is applied to the same portion throughout; however, I am aware that within the scope of 25 the claims there may be several modifications thereof.

Figure 1 is an end elevation of the key pulling device removing a key from an end 30 shafting.

Fig. 2 is a cross section on line 2—2 Fig. 1.

Fig. 3 is a side elevation of the device removing the same type of key from a through shafting.

35 Numeral 1 indicates an end portion of a rotary shafting, such as for example a line shafting in a machine shop which has the usual bearings not shown, and has secured thereon a mounted member, for example a 40 pulley 2, by a headed key 3. Coincident with the key is a keyway 4 for the end shafting and another keyway 5 is shown for a through shafting, and a keyway in the hub 7. The device consists of a metal block 8

45 which may be cast or drop forged, having a hollow portion 9 for clearing the head 10 of the key and an enlarged lip portion 11, which may be plain as shown or may have a knurled surface, for engaging the inner 50 face 12 of the key, and a further thinner lip portion 13 is at the opposite end for fitting into a narrower space than in which the portion 11 is shown; in such an event the jack screws 14 and 15 are reversed. For example 55 the device is shown adaptable for keys of one-half to three-quarters of an inch; but it

is to be understood that variable size devices may be similarly constructed for larger or smaller keys. Jack screws 14 and 15 are case hardened and have a liberal threaded 60 portion 16 engaging tapped holes 17 and are adjustable to bear against the face of the hub 7 of the pulley or gear that may be in place thereon, as shown in Fig. 3. The operation is as follows:—By turning the head 65 portion of the jack screws with a suitable wrench, the lip portion 11 draws on the inner face 12 of the key, as the jack screws 14 and 15 bear against the face of the hub 7, thereby removing the key from the coincident 70 keyways of the shaft and of the hub 7, the center line of pull being at or near the axis of the jack screws 14 and 15. The drawing is assisted by a set screw 18 threaded into a semi-circular portion of a yoke 19 75 having two extending straight ends with cap-screws 20 and 21 threaded therein which are fulcrumed in the slotted portions 22 and 23 in the block 8 which allow for the adjustment of the yoke and set screw 18 for 80 the proper holding position on either an end shaft as shown in Figs. 1 and 2, or a through shafting as shown in Fig. 3. It is to be noted that the lower portion of the block 8 is curved concentric with the shaft giving 85 a better proportion to the device, but it is to be understood that this may be straight. It is to be further understood that the yoke with its set screw may or may not be used in connection with the block, and may be 90 dispensed with in the extraction of large headed keys, for example over 1 $\frac{1}{4}$ ", the large holding area allowing for a firmer grip than in smaller keys where the yoke will materially assist in starting the key, preventing 95 it from binding.

Having thus described my invention what I claim as new and desire to secure by Letters Patent of the United States, is as follows:—

1. A key pulling device comprising a metal block having a hollow portion therein forming a lip portion integral therewith; said lip portion adaptable to engage the headed portion of a key securing two locked 105 members; an adjustable yoke having its ends fulcrumed onto said metal block; said block provided with adjustable jack-screws arranged in the side portions thereof; said jack-screws adaptable to bear upon one of 110 the locked members; said yoke provided with means to hold the device in its operating

position during the operation of the jack-screws for the extraction of the key from its secured position.

2. A key pulling device comprising a metal block having end lip portions; a jack screw in tapped holes on each side portion of said block; either of said end lip portions adaptable to engage the headed portion of a key securing a mounted member upon a rotary shafting; said jack screws being arranged to bear against the face of the hub of said mounted member for removing said key from its secured position.

3. A key pulling device comprising a metal block having a hollow portion therein with lips at each end thereof adaptable to engage the head of a key securing a mounted member on a rotary shafting; adjustable jack screws arranged into the side portions of said block adaptable for removing said key; a semi-circular yoke having ends with cap screws therein adaptable to engage slotted portions in the sides of said block; a

set screw threaded into the semi-circular portion of said yoke for the purpose of holding the device in its operating position.

4. A key pulling device for the extraction of a headed key from two locked members, comprising a metal block having an end lip portion integral therewith; said lip portion adaptable for engaging the headed portion of the key in its secured position; adjustable jack-screws arranged in the side portions of said metal block adaptable to bear upon one of the locked members, for the purpose of drawing the said lip portion upon the headed portion of the key for its extraction.

In testimony whereof I have hereunto set my hand on this 6th day of July, A. D. 1917, in the presence of the two subscribed witnesses.

CHARLES C. R. HAMMAR.
